UNITED STATES PATENT OFFICE.

FRANK SCHOBLE, OF PHILADELPHIA, PENNSYLVANIA.

DESIGN FOR A HAT.

48,505.

Specification for Design.

Patented Feb. 1, 1916.

Application filed July 16, 1915. Serial No. 40,338. Term of patent 14 years.

To all whom it may concern:

Be it known that I, FRANK SCHOBLE, a citizen of the United States, residing at Philadelphia, in the county of Philadelphia, and State of Pennsylvania, have invented a new, original, and ornamental Design for Hats, of which the following is a specification, reference being had to the accompanying drawings, forming part thereof, and in which,—

I claim:—

The ornamental design for a hat, as shown.

In testimony whereof I affix my signature hereto.

FRANK SCHOBLE.
